Primary Examiner — Sheryl Lane*Assistant Examiner* — Calvin E Vansant(74) *Attorney, Agent, or Firm* — Panitch Schwarze Belisario & Nadel LLP(57) **CLAIM**

The ornamental design for a dual vial adapter assemblage, as shown and described.

DESCRIPTION

FIG. 1 is a front top perspective view of a dual vial adapter assemblage, showing our new design;

FIG. 2 is a front bottom perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

The broken lines are directed to environment and form no part of the claimed design.

1 Claim, 7 Drawing Sheets# US D832,430 S
